UNITED STATES PATENT OFFICE.

WALTER F. GEOGHEGAN, OF GREAT NECK, NEW YORK, ASSIGNOR TO GILLIS & GEOGHEGAN, INC., OF NEW YORK, N. Y., A CORPORATION OF NEW YORK.

HOISTING APPARATUS.

Application filed January 19, 1924. Serial No. 687,168.

To all whom it may concern:

Be it known that I, WALTER F. GEOGHEGAN, a citizen of the United States, residing at Great Neck, in the county of Nassau and 5 State of New York, have invented a certain new and useful Improvement in Hoisting Apparatus, of which the following is a specification.

The invention relates to mechanism for 10 hoisting ashcans and other loads from a cellar floor to the sidewalk and is designed more particularly for service in buildings in which it is necessary to transfer such loads laterally through a cellar window to the 15 sidewalk level.

The object of the invention is to provide 20 simple, easily installed and operated means by which such transfer may be conveniently accomplished. A further object is to provide 25 means for reliably supporting the load in the window opening, above the sill, and presenting it in position for easy removal without damaging the sill or other portions of the window frame.

25 The invention consists in certain novel features and details of construction and arrangement by which the above and other objects are attained, to be hereinafter described and claimed.

30 The accompanying drawings form a part of this specification and show an approved form of the invention.

Figure 1 is a vertical section through a 35 portion of a cellar, showing the hoisting apparatus in elevation.

Figure 2 is a corresponding plan view, partly in horizontal section taken on the line 2—2 in Figure 1.

The remaining figures are on a larger 40 scale and show details of certain portions of the hoisting apparatus.

Figure 3 is a vertical section of the crane-standard, partly in elevation.

45 Figures 4 and 5 are horizontal sections taken on the lines 4—4 and 5—5 respectively in Figure 3.

Similar reference numerals indicate the same parts in all the figures.

The cellar floor is marked 10, and the 50 window opening in the wall of the cellar, above the sidewalk level, is marked 11. On the floor 10 in proper relation to the window opening is mounted a vertical post 12, preferably tubular, resting upon a foot 13 and 55 having a bracket 14 attached to the adjacent

wall 15 to aid in supporting it in the upright position. In the upper end of the post is inserted a flanged plug 16 having a raceway in its upper face for a circular series of anti-friction balls 17.

The upper portion of the post 12, above the bracket or brace 14, is inclosed loosely by a tube 18 of larger diameter having its upper end closed by a cap 19 on the under face of which is a hardened plate 20 resting upon the balls 17 and with the latter and the plug 16, serving as an antifriction step or bearing supporting the tube 18 and permitting its easy partial rotation upon and relatively to the post 12. The lower end of the 70 tube 18 is provided with a collar 21 incircling the post and serving to maintain the tube in position thereon.

The post 12 and tube 18 form the standard 75 for the laterally extended crane arm 22 fixed upon the tube and reinforced by a brace 23 extending from a fixed collar 24 on the tube to a point at the midlength of the arm. Brackets 25 loosely inclosing the tube and attached to the wall 15 maintain the tube 80 and its inclosed post in the vertical position.

Fixedly mounted on the tube 18 near its lower end is a windlass, only partially represented, comprising a frame 26 in which is a gearwheel 27 on a shaft 28 which also carries the winding drum 29, indicated in dotted lines in Figure 1. The gearwheel and drum are rotated by a pinion 30 on a shaft 31 in mesh with the gearwheel and turned by a crank 32 on the shaft 31. This winding mechanism may be of any approved type 90 mounted to rotate with the tube 18, and may be understood to be provided with a brake mechanism and holding pawl and other equipments as usual.

From the drum 29 the hoisting cable 33 extends vertically to and over the pulleys 34 and 35 in the crane arm 22, and its depending end carries a hook 36 adapted to engage the load to be hoisted, shown as an ashcan 37. By turning the crank 32 the can may be raised or lowered, and by lateral pressure on the frame 26 in one direction or the other, the windlass, tube 18, and crane arm 22 may be swung correspondingly, the tube 18 partially rotating upon the fixed post 12 to permit such movements. The crane arm lies a little lower than the lintel or top of the window opening 11.

On the tube 18 and loosely inclosing it 110

- is a sleeve 38 rotatably supported at its lower end on the lowermost bracket 25 and having at its midheight an annular swell 39 the interior of which provides an annular recess 40 in which is received the convolutions of a helical expansion spring 41, one end 43 of which is engaged in a radial hole in the tube 18, and the other end 49 lies against one end of a wide peripheral slot 10 or opening 44 in the swell 39. At the top of the sleeve 38 is fixed a radial bracket 45 carrying a shelf or platform 46 supported at a height slightly above the window sill of the opening 11.
- 15 The crane arm 22 and bracket 45 both extend radially but at an angle to each other normally, due to the action of the spring 41 the tension of which is exerted to rotate or partially turn the tube 18 and sleeve 20 38 relatively to each other, the extent of such movement being determined by a stop pin 47 set in the tube 18 and extending radially into a peripheral slot 48 in the swell 39 of the sleeve 38. Such expansive force holds the bracket 45 and crane arm 22 normally in the angular positions shown by the dotted lines at A in Figure 2 and by the full lines in the same figure, but such engagement is yielding in the direction to 30 bring the crane arm 22 and bracket 45 into vertical alignment by arresting the movement of the bracket and continuing the movement of the arm in such direction.
- The operation is as follows:—The crane arm 22 and platform 46 being in the position shown at A in Figure 1 in the dotted lines, the hook 36 is lowered and attached to the can 37; the latter is then raised to a height slightly above the level of the platform 46, see Figure 1, by the rotation of the hoisting drum 29, and held thus suspended, then, by pressure of the operator against the frame 26, the tube 18 with its crane arm 22 and the sleeve 38 with its platform 46 are swung as one toward the window opening 11 but at an angle to each other until the bracket 45 strikes the jamb or side of the window opening and is arrested; by continuing the rotation of the tube 18 the crane arm 22 overtakes the platform, against the tension of the spring 41, and with its load is swung over the platform 46 within the window opening, as indicated by the dotted lines at B in Figure 2. While still maintaining the pressure and holding the crane arm in this position, the can is lowered upon the platform and is supported thereby, and on slackening the cable 33, or by disengaging the hook 36 50 55 60 65 from the can, with the aid of an assistant on the sidewalk, and relaxing the pressure on the frame 26, the tube 18 is partially rotated in the reverse direction relatively to the sleeve by the expansion of the spring 41, thus automatically moving the crane

arm 22 back to the position shown in full lines in Figure 2, leaving the can deposited on the platform 46 ready for removal. An empty can from the sidewalk may be placed on the platform, the hook engaged therewith, and the whole swung inwardly with the empty can presented in position for lowering.

It will be noted that the operation may be performed by a single operator who may raise the can, deposit it on the platform and then ascend to the sidewalk and remove it. Also that the platform protects the window sill and offers a substantial and level support for the can while awaiting removal, and that the apparatus may be swung inwardly clear of the window opening out of the path of a window sash in opening or closing the latter.

The apparatus is especially adapted for service in buildings having no sidewalk hoistway, in which the cans are to be delivered through a side window, and is designed to be easily installed in such situations.

I claim:—

1. An ash-hoist comprising a vertically disposed member, a crane arm mounted thereon for swinging movement, a swinging platform supported from said member and movable independently of said crane arm, and resilient means cooperable with said platform whereby said platform and crane arm move in unison.

2. An ash-hoist comprising a vertically disposed member, a crane arm mounted thereon for swinging movement, a swinging platform supported from said member and movable independently of said crane arm, and resilient means cooperable with said platform whereby said platform and crane arm move in unison for a portion only of their travel.

3. An ash hoist which comprises a post located in a cellar, a swinging crane arm mounted thereon, and means adapted to swing said arm with its load through an opening in the wall of said cellar, and a platform mounted on said post and arranged to swing into said opening in advance of said crane arm and to stop in position to be in vertical alignment with the load carried by the crane arm when the latter completes its travel.

4. An ash hoist which comprises a post, a tube inclosing said post and rotatably mounted thereon, a crane arm on said tube, and a platform rotatably mounted on said tube.

5. An ash hoist which comprises a post, a tube inclosing said post and rotatably mounted thereon, a crane arm on said tube, a platform rotatably mounted on said tube, and resilient means acting upon said platform and tube to hold said crane arm and

platform yieldingly out of vertical alinement relatively to each other.

6. An ash hoist which comprises a post, a tube inclosing said post and rotatably mounted thereon, a horizontally swinging crane arm on said tube, a sleeve loosely inclosing said tube, a horizontally swinging bracket on said sleeve, and a platform on said bracket, a spring engaged with said

tube and sleeve and arranged to hold said 10 crane arm and platform yieldingly out of vertical alinement relatively to each other, and to permit partial rotation of said tube and sleeve relatively to each other, and a stop for limiting such partial rotation. 15

In testimony that I claim the invention above set forth I affix my signature hereto.

WALTER F. GEOGHEGAN.
